US00D959082S

(12) **United States Design Patent** (10) **Patent No.:** **US D959,082 S**
Lambertson, Jr. et al. (45) **Date of Patent:** **** Jul. 26, 2022**

(54) **COATING MATERIAL CONTAINER**

- (71) Applicant: **SWIMC LLC**, Cleveland, OH (US)
(72) Inventors: **Michael C. Lambertson, Jr.**, Aurora, OH (US); **Joshua R. Robertson**, North Ridgeville, OH (US); **Yubing Lu**, Ningbo (CN)
(73) Assignee: **SWIMC LLC**, Cleveland, OH (US)
(**) Term: **15 Years**
(21) Appl. No.: **29/786,523**
(22) Filed: **Jun. 1, 2021**

Related U.S. Application Data

CLAIM

The ornamental design for a coating material container, as shown and described.

DESCRIPTION

FIG. 1 is a top perspective view of an embodiment of a coating material container showing a new design; FIG. 2 is a bottom perspective view of the coating material container illustrated in FIG. 1.

FIG. 3 is a front view of the coating material container illustrated in FIG. 1;

FIG. 4 is a rear view of the coating material container illustrated in FIG. 1;

FIG. 5 is a left side view of the coating material container illustrated in FIG. 1;

FIG. 6 is a right side view of the coating material container illustrated in FIG. 1;

FIG. 7 is a top view of the coating material container illustrated in FIG. 1; and,

FIG. 8 is a bottom view of the coating material container illustrated in FIG. 1.
